UNITED STATES PATENT OFFICE.

HAROLD O. SMITH, OF INDIANAPOLIS, INDIANA, ASSIGNOR TO THE RACINE HORSE-SHOE TIRE COMPANY, OF RACINE, WISCONSIN, A CORPORATION OF WISCONSIN.

DESIGN FOR A RESILIENT TIRE.

Application filed January 19, 1923. Serial No. 4,935. Term of patent 14 years.

To all whom it may concern:

Be it known that I, HAROLD O. SMITH, a citizen of the United States, residing at Indianapolis, in the county of Marion and State of Indiana, have invented a new, original, and ornamental Design for Resilient Tires, of which the following is a specification, reference being had to the accompanying drawing, forming a part thereof.

In the drawings Figure 1 is a plan view looking upon a section of a tire showing my new design;

Figure 2 is a longitudinal section on the line 2—2 of Figure 1.

I claim:

The ornamental design for a resilient tire, as shown.

HAROLD O. SMITH.
